OR D 13,010

DESIGN FOR A FIRE-BACK AND JAMB.

Design No. 13,010, dated June 27, 1882.

UNITED STATES PATENT OFFICE.

WILLIAM D. HEWITT, OF BURLINGTON, N. J., ASSIGNOR TO WILLIAM H. HARRISON & BROTHER, OF PHILADELPHIA, PA.

DESIGN FOR A FIRE-BACK AND JAMB.

SPECIFICATION forming part of Design No. 13,010, dated June 27, 1882.

Application filed March 20, 1882. Term of patent 7 years.

To all whom it may concern:

Be it known that I, WILLIAM D. HEWITT, a citizen of the United States, residing at Burlington, in the county of Burlington, State of New Jersey, have invented and produced a new and original Design for Fire-Backs and Jambs, of which the following is a specification, reference being had to the accompanying photographic illustration, forming part thereof.

10 A represents the fire-back, and B the jambs. On the face of the fire-back and jambs are squares *a*, which are striated, the striations of one square extending at a right angle to those of the contiguous square, or, in other words, 15 the striations extend vertically and horizontally in alternate squares.

b represents rosettes edged with leaves *c*, the stems of which have scrolls *d*, the buttons *b'* of the rosettes being eccentric.

20 *e* represents scallops alternating in adjacent rows, and *f* represents festoons alternating in adjacent rows and interposed between the rows of scallops..

I claim—

1. The design for fire-back and jamb, having striated squares *a* and rosettes *b*, the striations extending vertically and horizontally in alternate squares, substantially as set forth. 25

2. The design for fire-back and jamb, having rosettes *b*, the buttons *b'* of which are eccentric, substantially as set forth. 30

3. The design for fire-back and jamb, having rosettes which are edged by leaves *c*, substantially as set forth.

4. The design for fire-back and jamb, having leaves, the stems of which have scrolls *d* connected to them, substantially as set forth. 35

5. The design for fire-back and jamb, having scallops *e* and festoons *f*, alternating in adjacent rows, substantially as set forth. 40

6. The design for fire-back and jamb, having striated squares *a*, rosettes *b*, leaves *c*, scrolls *d*, scallops *e*, and festoons *f*, as shown and described.

WM. D. HEWITT.
